REFINING OF HYDROCARBON DISTILLATES

Robert C. Arnold, Park Forest, Ill., and Arthur P. Lien, Highland, Ind., assignors to Standard Oil Company, Chicago, Ill., a corporation of Indiana

Application October 24, 1951, Serial No. 252,912

7 Claims. (Cl. 196—30)

This invention relates to the treatment of hydrocarbon distillates which contain organic sulfur compounds and aromatic hydrocarbons. More particularly, the invention is directed to the treatment of petroleum oils boiling in the heavier-than-gasoline range which contain undesirable amounts of aromatics and organic sulfur compounds. The invention is of especial interest for the treatment of distillate fuels, i. e., oils boiling in the range of 300 to 650° F. such as heavy naphtha, kerosene, diesel oil, furnace oil and heater oil.

Practically all hydrocarbon oils derived from natural sources consist of paraffins, naphthenes, aromatics, organic sulfur compounds and some organic nitrogen and oxygen compounds. For some purposes the presence of aromatics is desirable, e. g., gasolines and high solvency naphthas. For other uses the presence of large amounts of aromatics is objectionable, e. g., burning oils and domestic fuel oils. For most common uses of hydrocarbon oils the presence of organic sulfur compounds is objectionable even though small amounts are tolerated. The magnitude of the problem is illustrated by the fact that heater oil obtained from West Texas crude contains about 20% of aromatic hydrocarbons and about 4% of organic sulfur compounds—its total sulfur content being about 0.7 wt. percent. Sulfur contents up to about 1.5% are not uncommon.

A very large number of processes for reducing sulfur and aromatic content of hydrocarbon distillates have been developed such as sulfuric acid treating, silica gel extraction, liquid SO₂ extraction, liquid HF extraction, etc. Liquid HF extraction removes organic sulfur compounds and some of the polynuclear aromatic compounds. Liquid SO₂ extraction removes aromatic hydrocarbons and organic sulfur compounds, but the selectivity for the sulfur compounds is so low that in order to produce an acceptable low-sulfur oil, it is necessary to take a prohibitive loss of the feed stock to extract.

An object of our invention is to refine hydrocarbon distillates by substantially reducing the amount of both organic sulfur compounds and aromatic compounds present therein. Another object is to produce a domestic fuel oil of good burning quality and odor by removing organic sulfur compounds and aromatic compounds therefrom.

We have found that a low-sulfur oil of good burning quality can be obtained from a high-sulfur, high-aromatic content distillate without excessive treating loss by contacting said distillate at a temperature below about 10° C. with a treating agent consisting of an aluminum chloride-hydrocarbon complex and sufficient liquid sulfur dioxide to obtain a two-phase separation wherein the extract phase consists of liquid SO₂, AlCl₃ complex and extract materials.

It is well known that substantially anhydrous AlCl₃ will form an adduct with many organic compounds, particularly olefinic and aromatic hydrocarbons. These adducts are commonly referred to as complexes. Many well known processes use an AlCl₃-hydrocarbon complex

2

as a catalytic agent in carrying out chemical reactions such as alkylation, polymerization, isomerization, cracking, etc. The complex formed by the reaction of AlCl₃ and a hydrocarbon such as olefin, aromatic, paraffin or naphthene may contain from about 25 to about 75 wt. percent of AlCl₃. In some cases the amount of AlCl₃ is increased above the stoichiometric amount by dissolving additional amounts of AlCl₃ in the complex. In general these complexes are clear, mobile liquids ranging in color from yellow to red.

A complex when used as a catalyst for hydrocarbon conversions gradually loses its activity and becomes spent. Usually as the activity of the complex declines, the hydrocarbon content of the complex increases. However, a complex that is spent for one type of reaction may be active for catalyzing a different type of reaction, e. g., a spent alkylation complex can be used to catalyze polymerization of isobutylene.

It is known that AlCl₃-hydrocarbon complexes have a selective solvent action for the naphthenic and the aromatic constituents of lubricating oil fractions. However, we have found that the complex has relatively little effectiveness in desulfurizing hydrocarbon distillates and in particular those distillates in the heavier-than-gasoline range, such as, heater oil and kerosene. We have discovered that a treating agent consisting of an AlCl₃-hydrocarbon complex and liquid SO₂ will give a greater degree of desulfurization of a petroleum distillate than will the sum of the desulfurization effects of either of the two treating agents alone. Furthermore, we have discovered that not only will a freshly prepared complex in combination with liquid SO₂ produce an effective amount of desulfurization, but also partially spent complexes, or those which are completely spent for some particular catalytic purpose, will produce an effective amount of desulfurization when used in combination with liquid SO₂.

The AlCl₃-hydrocarbon complex can be prepared by contacting substantially anhydrous AlCl₃, preferably in the presence of hydrogen chloride, with various hydrocarbons; for example, olefins, such as isobutylene; certain paraffins, such as isooctane; aromatics; or mixtures of these hydrocarbons. The complex should contain in excess of 25 wt. percent of AlCl₃ and preferably in excess of about 50% of AlCl₃. While freshly prepared complex can be used in our process, we prefer to operate with a spent complex obtained from some other process using a complex as a catalyst; the spent complex should contain preferably between 50 and 75 wt. percent AlCl₃.

Some desulfurization can be obtained by using as little as 0.5 gram mol of AlCl₃, in the form of an AlCl₃-hydrocarbon complex, per gram atom of sulfur present in the raw oil. Virtually complete desulfurization is obtainable for oils of sulfur content up to about 1.5 wt. percent by using between 3 and 5 or more mols of AlCl₃ per gram atom of sulfur present in the raw oil. (Hereafter it is to be understood that the term "mols of AlCl₃" refers to gram mols of AlCl₃ present in an AlCl₃-hydrocarbon complex per gram atom of sulfur in the raw oil.) Normally a sufficiently low sulfur product oil can be obtained by using from about 1 to about 3 mols of AlCl₃.

We have found that the burning quality of a high-sulfur, high-aromatic heater oil is markedly improved by the removal of even a small amount of aromatic compounds when using a treating agent consisting of an AlCl₃-hydrocarbon complex and liquid SO₂. Considerable improvement in burning quality is obtained when using only enough liquid SO₂ to obtain a two-phase separation of raffinate oil and extract phase. The minimum amount of liquid SO₂ needed is about that amount soluble in the raw oil in the absence of complex. For example, at a treating temperature of about —35° C.,

about 14 volume percent of liquid SO₂ is soluble in a West Texas heater oil. However, some improvement in desulfurization and burning quality is obtainable when using even smaller amounts of liquid SO₂ since an SO₂-rich phase appears when the complex is added to a saturated solution of SO₂ and oil. At a fixed complex usage the extent of desulfurization increases markedly with increase in liquid SO₂ usage up to about 25 volume percent based on raw oil; above this point the gain in desulfurization per unit of additional SO₂ usage is small, and about 100 volume percent is about the maximum desirable amount of liquid SO₂. In some cases where not only maximum desulfurization but also maximum dearomatization is desired, the liquid SO₂ usage may be as much as 500 volume percent. In general, we prefer to use from at least enough liquid SO₂ to exceed the solubility of SO₂ in the raw oil and preferably about 25% to about 100 volume percent of liquid SO₂ based on raw oil.

The effectiveness of the liquid SO₂-AlCl₃ complex treating agent is substantially independent of temperature below about 0° C. Above 0° C. the effectiveness of the treating agent decreases rapidly, and about 10° C. is the highest temperature at which reasonable effectiveness can be maintained. In addition to the effect on desulfurization and dearomatization, temperature has an effect on the color of the final oil. At temperatures of about -20° C. and below, final oils of substantially water white color are obtainable. The color of the product oil darkens markedly as the temperature of contacting increases until at about 0° C. the product oil is no better in color than the raw oil. We prefer to operate our process at temperatures below about 0° C. and preferably below about -20° C.

The time of contacting of the treating agent and the raw oil is dependent upon the intimacy of the contacting and also somewhat upon the contacting temperature. Ordinarily the contacting time will be between about 1/2 minute and 60 minutes; usually about 5 minutes will be sufficient.

When the raw distillate is very viscous or of high pour point, it may be desirable to dilute the feed with a low boiling hydrocarbon, such as butane, pentane, hexane, petroleum ether, etc. The diluent should be inactive toward the treating agent.

Our refining process can be used for various petroleum feed stocks, such as naphthas, kerosenes, heater oils, gas oils and lube oils. It is of particular use in treating distillates in the heavier-than-gasoline boiling range, i. e., 300 to 650° F. Our process can be used not only on virgin stocks, but also on oils obtained from various conversion processes, e. g., thermal cracking and coking, catalytic cracking, products of other solvent extraction processes, etc. The high olefin content of thermally cracked oils interferes somewhat with the phase separation in our process even though these oils can be used therein. Catalytically cracked oils are particularly suitable for treatment by our process because they contain large amounts of refractory sulfur compounds and aromatic compounds. In general any hydrocarbon oil containing excessive amounts of organic sulfur compounds is a suitable feed for our process.

The product oil from our process is an excellent feed to a catalytic cracking operation because of its very low sulfur content and low aromatic content. In some cases our process can be used for the sole purpose of upgrading undesirable stocks and making them suitable for use in the catalytic cracking operation.

The extract phase from our process consists of liquid SO₂, AlCl₃ complex, organic sulfur compounds and hydrocarbons. The organic sulfur compounds and hydrocarbons can be recovered from the extract phase by removing the SO₂ and hydrolyzing the complex with water or preferably a dilute hydrochloric acid solution. The extract oil obtained by the decomposition of the extract phase is very high in sulfur content and may contain from 4 to 8% sulfur. Another method of treatment of

the extract phase is to remove the SO₂ and then to distill some of the hydrocarbons and sulfur compounds away from the complex; in this method of operation the temperature of the SO₂-free material should be maintained at less than about 400 to 500° F. in order to avoid excessive cracking of the materials and coke formation in the vessel. The amount of cracking may be reduced by carrying out this operation under vacuum. By this procedure it is possible to recover a substantial percentage of hydrocarbons containing less sulfur than the sulfur content of the total extract oils.

We have found that removal of a portion of the SO₂ from the extract phase results in a two-phase separation of a second raffinate phase and a second extract phase. The second raffinate phase consists of mainly aromatic hydrocarbons; the hydrocarbons in the second raffinate phase have a sulfur content much lower than the sulfur content of the total extract oil, and in some cases less than 1%. The second extract oil obtained by removing the remaining SO₂ and by hydrolyzing the AlCl₃ complex consists mainly of organic sulfur compounds containing in some cases as much as 12% sulfur.

We have found that the second raffinate oil is an excellent feed to a catalytic cracking operation. When this oil is catalytically cracked, a very high yield of high octane number naphtha is obtained; and this naphtha has a remarkably low sulfur content, in some cases less than 0.05%.

Also, we have found that when a maximum yield of low sulfur product oil is desired without regard to dearomatization, the yield of the product oil can be markedly increased without substantial increase in sulfur content by recycling the second raffinate oil to the initial contacting step.

The following data are given to illustrate the results obtainable by our process. The feed stock in each instance was a virgin West Texas heater oil with the following characteristics:

30	API	40.9
30	Sulfur (wt. percent)	0.61
30	n_D^{20}	1.4558
30	Color, Saybolt	+13
30	ASTM distillation:	
45	IBP	° F. 330
45	50%	° F. 450
45	Max	° F. 555

Five hundred ml. of this oil was added to a reactor provided with a cooling jacket and a mechanical agitator. In each run the temperature of the reactor contents was maintained at -20° C. The contents of the reactor were agitated for about 5 minutes and were then allowed to settle for 30 minutes. The extract phase and the raffinate phase were withdrawn separately. The raffinate phase was washed with water, then with 10% aqueous caustic, then with water again and finally dried by blowing nitrogen through the oil. This procedure removed all traces of SO₂. The extract phase was decomposed by removing the SO₂ and hydrolyzing the substantially SO₂-free material with cold water. For purposes of comparison, runs were made with liquid SO₂ alone and with AlCl₃-hydrocarbon complex alone containing 65 wt. % AlCl₃, which complex was obtained by reacting AlCl₃ and isoctane. Two mols of AlCl₃ per gram atom of sulfur in the feed were used. Lastly, the oil was treated with the same amount of liquid SO₂ and complex together as used in Runs 1 and 2.

70	Run	AlCl ₃ as Complex	SO ₂ , V Percent on Oil	Raffinate Yield	Percent Desulfurization	Raffinate n_D^{20}
		Mols	Percent			
1		2	50	88	39	1.4461
2		2	90	90	18	1.4946
3		2	88	88	70	1.4460

The percent desulfurization obtainable in the absence of the synergistic effect of our treating agent would have been about 51%.

In order to more fully describe a specific embodiment of our invention, reference is made to the accompanying drawing which constitutes a part of this specification and in which a schematic flow diagram of our process is shown.

The feed stock, for example, a virgin heater oil distillate from a West Texas crude, from source 11, is passed through line 12 into a drying zone wherein it is substantially dehydrated. The presence of water in the treating system is extremely undesirable because water reacts with the AlCl_3 -hydrocarbon complex and also water increases the corrosive tendencies of liquid SO_2 . Drying zone 13 comprises conventional equipment, such as, a vessel packed with calcium chloride, alumina, or the like.

The dried distillate is passed through line 14 into deaeration zone 16, wherein air dissolved or entrained in the feed is substantially removed. Conventional equipment such as is ordinarily employed in commercial processes of liquid SO_2 refining of hydrocarbon oils may be employed in zone 16. The dried, deaerated distillate is passed through line 17 into heat exchanger 18, wherein the temperature of the feed is lowered to the desired treating temperature; herein we operate at -20°C .

In the case of very viscous distillates, the viscosity can be reduced by dilution with a hydrocarbon oil that is inert to the treating agent. Suitable diluents are butane, pentane, petroleum ether, etc. The diluent, from source 21, may be introduced by way of valved line 22 into line 17.

The dried, deaerated (diluted) distillate is introduced by way of line 19 into the lower portion of extraction tower 26. Tower 26 may be packed with corrosion resistant materials, such as Raschig rings or Berl saddles, or may be of modified bubble cap type construction. Instead of a tower, we can use a series of batch counter-current vessels. In tower 26, the feed is contacted with a treating agent consisting of liquid SO_2 and an AlCl_3 -hydrocarbon complex, which complex contains about 60 wt. percent of AlCl_3 . Although the liquid SO_2 and the complex can be added to tower 26 as separate streams, we prefer to combine them and introduce the mixture into the tower.

In this example, liquid SO_2 , 50 volume percent based on distillate, from source 28 is passed through lines 29 and 31 into mixer 32. The AlCl_3 -hydrocarbon complex, 2 gram mols of AlCl_3 per gram atom of sulfur in the feed distillate, from source 33 is passed through line 34 into mixer 32, where the complex and the liquid SO_2 are commingled. From mixer 32 the treating agent passes by way of line 36 and into tower 26 through any one or all of valved manifold lines 37, 38 and 39.

The temperature in tower 26 is maintained in this example at about -20°C . Sufficient pressure is maintained on the system to keep the SO_2 liquid, even though the temperature of contacting may be above the boiling point of liquid SO_2 , i. e., -10°C . at 15 p. s. i. a. The contacting period in tower 26, in this example, is 10 minutes.

The raffinate phase, consisting of hydrocarbon and some SO_2 dissolved therein, passes out of tower 26 by way of line 46 to stripper 47. In stripper 47, the SO_2 is driven off by raising the temperature of the raffinate phase to about 200°F . by means of internal heater 48. The SO_2 passes out of stripper 47 through line 49. The low sulfur product oil passes out of stripper 47 through line 51 to storage, not shown.

The extract phase, consisting of liquid SO_2 , AlCl_3 complex, organic-sulfur compounds and hydrocarbons, passes out of tower 26 through line 54, through heat exchanger 56 and through line 57 into a vessel 58. The extract phase is heated so that a portion of the SO_2 will be flashed as the extract phase enters vessel 58. Vessel 58 is provided with a pancake coil 59 which serves

to condense any hydrocarbons that may be vaporized along with the SO_2 so that only SO_2 passes out of vessel 58 by way of line 61. Sufficient SO_2 must be removed to cause the formation of two phases; in this example we remove about one-half the SO_2 from the extract phase by means of the flashing operation in vessel 58.

The bottoms from vessel 58 are passed through line 64 into a settler 66. In settler 66 there exists a second raffinate phase consisting of some SO_2 , hydrocarbons—mainly aromatics, and some organic-sulfur compounds; also present is a second extract phase consisting of liquid SO_2 , complex, organic-sulfur compounds and some hydrocarbons. From settler 66, the second raffinate phase is passed through lines 68 and 69 into stripper 71.

In stripper 71, the SO_2 is removed by heating the raffinate to about 200°F . by means of internal heater 72; the SO_2 passes out through line 73. The bottoms from stripper 71 consist mainly of aromatic hydrocarbons, some non-aromatic hydrocarbons, and some organic-sulfur compounds. In general, the sulfur content of the second raffinate oil is considerably less than the sulfur content of the total extract oil. The second raffinate oil—low sulfur extract—passes to storage by way of line 74.

In some cases, maximum yield of low sulfur product may be the object of the treatment. This object can be attained by recycling the second raffinate phase from settler 66 by way of line 68 and 76 to a lower part of tower 26. By this method of operation, the yield of product oil from stripper 47 is increased with substantially no increase in sulfur content over the no-recycle operation.

The second extract phase from settler 66 is passed through line 81 into stripper 82. Substantially all the SO_2 is removed by heating the extract phase to between about 150 and 250°F . under a pressure that permits vaporization of the SO_2 alone, i. e., between about 25 and 100 p. s. i. a., by means of internal heater 83. The temperature in the bottom of stripper 82 should be maintained as low as possible in order to reduce the cracking of both hydrocarbons and sulfur compounds. The vapors from stripper 82 pass out through line 84.

The essentially SO_2 -free bottoms in stripper 82 pass out by way of line 86 to mixing vessel 87. Dilute aqueous HCl , for example, 10%, from source 91 is passed through lines 92 and 93 into mixer 87. The AlCl_3 -containing bottoms are decomposed by the aqueous HCl to form a hydrocarbon and organic-sulfur compound oil and an aqueous solution of AlCl_3 reaction product. We could use water for the decomposition but prefer to use aqueous HCl because the reaction is not as vigorous, and because aqueous HCl prevents formation of gelatinous aluminum hydroxide. Mixer 87 should be provided with a cooling coil, not shown, if water is to be used to decompose the AlCl_3 -containing extract.

The mixture from vessel 87 is passed through line 96 into settler 97 where a high sulfur extract layer and an aqueous layer separate. From settler 97 there is vented through line 98 a stream of H_2S , SO_2 water vapor and minor amounts of HCl , which materials were released in the decomposition procedure. The high sulfur extract, consisting mainly of organic-sulfur compounds, is sent to storage or to further treatment by way of line 99. The aqueous solution is sent to waste disposal by way of line 101.

Usually the streams in lines 84 and 98 contain some water, which water must be removed in order to permit reuse of the SO_2 contained in these lines. The streams from lines 84 and 98 are passed into a gathering line 106 which leads to a dehydration zone 107. From time to time, it may be necessary to remove water from the SO_2 streams in lines 49, 61 and 73. In such a case, the streams from lines 49, 61 and 73 are passed through gathering line 111, valved line 112 and line 106 to dehydration zone 107.

The water from dehydrator 107 will contain acidic ma-

terial and this solution is passed via lines 114 and 93 to the decomposition vessel 87.

The dehydrated stream from zone 107 is passed through line 116 to a purification zone 117. Normally the streams in lines 49, 61 and 73 pass directly by way of line 111, valved line 119 and line 116 to zone 117. In purification zone 117, the SO₂ and H₂S are separated, for example, by fractional liquefaction because of the spread between the boiling points of these compounds. From zone 117, the liquid SO₂ is recycled to the extraction system via lines 121 and 31. The H₂S is discarded or sent to sulfur recovery by way of line 122.

It should be understood that many details of process technique have been omitted in the above specific embodiment of our process. Many variations thereon will suggest themselves to those skilled in the art and such expedients are within the purview of the present invention.

We claim:

1. A process for refining a virgin hydrocarbon distillate in the heavier-than-gasoline range which contains objectionable amounts of organic-sulfur compounds and aromatic compounds, which process comprises contacting said distillate at a temperature below about 0° C. with a liquid treating agent consisting essentially of 14-500 volume percent of liquid SO₂, based on said distillate, and an AlCl₃-hydrocarbon complex containing between about 25 and 75 wt. percent of AlCl₃, in an amount equal to between 0.5 and 5 mols of AlCl₃ per gram atom of sulfur in said distillate, separating a raffinate phase from an extract phase comprising liquid treating agent, hydrocarbons and sulfur compounds, removing occluded and dissolved treating agent from said raffinate phase to recover a product containing less sulfur and less aromatics than said distillate and treating said extract phase to recover SO₂.

2. The process of claim 1 wherein the temperature of contacting is below about -20° C.

3. The process of claim 1 wherein the amount of liquid SO₂ is between about 25 and 100 volume percent.

4. The process of claim 1 wherein said complex contains between about 50 and 75 wt. percent of AlCl₃.

5. The process of claim 1 wherein said complex is present in an amount equal to between 1 and 3 mols of AlCl₃ per gram atom of sulfur in said distillate.

6. The process of claim 1 wherein said complex has been previously used as a hydrocarbon conversion catalyst and is essentially spent for such use.

7. The process of refining a high sulfur and high aromatic content virgin heater oil distillate which process comprises contacting said distillate with a liquid treating agent consisting essentially of liquid SO₂, about 50 to 100 volume percent based on said distillate, and an AlCl₃-hydrocarbon complex which contains about 65 wt. percent of AlCl₃, in an amount equal to about 2 to 3 mols of AlCl₃ per gram atom of sulfur in said distillate, at a temperature of contacting at about -20° C., separating a raffinate phase from an extract phase comprising liquid treating agent, hydrocarbons and sulfur compounds, removing occluded and dissolved treating agent from said raffinate phase to recover a product oil of satisfactorily low-sulfur content and of good burning quality, and treating said extract phase to recover SO₂ and the hydrocarbon and sulfur compounds therefrom.
